UNITED STATES PATENT OFFICE

2,453,250

LIPSTICK CONTAINER

Charles Nehrke, New York, N. Y.

Application August 14, 1945, Serial No. 610,725

2 Claims. (Cl. 206—56)

1

This invention relates to lipstick containers. Broadly, it is an object of my invention to provide a lipstick container which can be operated with one hand.

More particularly, it is an object of my invention to provide a lipstick container which is completely closed, retaining the lipstick within the container in a sanitary manner and completely covered. By a movement of the thumb, the cover opens and causes the lipstick to be propelled outwardly for immediate use. A reverse movement of the thumb causes the lipstick to be repelled and housed within the container and causes the cover to snap into closed position.

A further object is to provide an inexpensive lipstick container which can be cheaply and inexpensively assembled.

For a fuller understanding of the nature and objects of my invention, reference is had to the following detailed description in connection with the accompanying drawings, in which:

Fig. 1 is a side sectional elevation.

Fig. 2 is a front elevation partly in section.

Fig. 3 is a top view.

Fig. 4 is a horizontal section.

Fig. 5 is a side sectional elevation showing the cap in its downward position with the lipstick ejected.

Fig. 6 is a side sectional view partly broken away of a modified container.

Fig. 7 is a side sectional view of the upper portion of the container showing the position of the cap as it is being opened.

Referring to the drawings, numeral 10 represents a lipstick container which is comprised of two parts, 11 and 12, split longitudinally for housing the lipstick. These parts, when the lipstick container is assembled, are held together by a plastic adhesive, or if desired, by a slideable and removable band 13, which may be of metal or plastic. Within the container there is slideably mounted a cup 14 for receiving the lipstick mass

15. Cup 14 has a recess at the base thereof for receiving the end of the lipstick mass 15 and also has a projection 16 which slides longitudinally within a groove 17 within the housing 11 and 12. Attached to projection 16 there is a flexible band 18 which may be of metal or plastic and which slides within the groove 17 which runs from the front to the back of the container and around the bottom. The opposite end of the flexible band 18 is attached to pin 20 at the base of the cap 21 so that downward movement of the cap 21 will cause the band 18 to move within channel 17 causing an upward pressure upon projection 16, thus

2

causing base member 14 to rise upwardly and propel the lipstick mass 15 through the upper opening of the container.

By sliding cap 21 upwardly with the thumb, a reverse motion takes place causing the lipstick mass 15 to be repelled and slide into the container since cup 14 is drawn downwardly by the spring 18 pulling projection 16. Cap 21 slides within a channel 26 provided in the rear walls 10 of the container.

At the bottom of the housing, there is a recess 22, in which is disposed a coiled spring 23. This spring normally urges the cup 14 upwardly. When the cup 14, in its downward movement strikes the top of the coiled spring 23, the cup 14 will rebound upwardly causing the lug 16 to move the left end of the flexible spring band 18 upward, thus causing the right side of the flexible spring band to pull upon the pin 20, thus exerting a downward pressure upon the cap 21 which pivots about the pin 20 so as to cause the cap to snap closed upon the open upper end of the housing. It is, of course, understood that the cap is positioned at the side of the top of the housing when the cup 14 strikes the coiled spring 23, to assure the snap closing of the cap.

My lipstick container is readily assembled because it is split longitudinally. In order to assemble the same, one-half of the housing 11 receives the cap, band 18 and cup 14 which contains the lipstick mass. Spring 23 is inserted into the recess and the other wall of the housing 12 completes the assembly. To retain the two walls 11 and 12 of the housing together, a projection 24 at the bottom of one-half of the housing is provided for entry into a cooperating recess 25 so that the two walls of the housing 11 and 12 are accurately aligned. A tongue 28 at the top of the housing falls into the end of the channel 17 to help hold the housing together. A binder such as an acetate can be used to firmly hold the housing together.

An advantage of having a vertically split housing permits the use of different colors for the different housing walls and also that of the cap so that interesting and pleasing color schemes can be achieved, especially with plastics.

In Fig. 6, I have provided a resilient material 27 which may be of rubber or a resilient plastic as a substitute for the spring 23.

It is obvious that various changes and modifications may be made in the details of construction without departing from the general spirit of the invention.

I claim:

1. A lipstick container comprising a housing open at its top, a movable cup arranged in said housing, a spring in the base of said housing for exerting an upward pressure upon said cup, a lipstick mass within the cup, a movable cap for the open top of the housing, a sliding flexible strip connecting the movable cap to the movable cup for moving the latter upwardly in the housing to project the lipstick mass above the open top of the housing for use, said flexible strip and spring coacting to snap the cap shut when the cap is in a predetermined position at the open upper end of the housing, said housing being provided with longitudinal guide means for the flexible strip and for the movable cap, said open top of the housing having a seat substantially at right angles to the guide means, the lower portion of one end of the cap being pivotally connected to one end of the flexible strip, said connection being substantially in line with the guide means when the cap is in a closed position on said seat, said spring causing the cup to rebound when the cup is moved to its lowered position within the housing.

2. A lipstick container comprising a housing open at its top, a movable cup arranged in said housing, a resilient means in the base of said housing for exerting an upward pressure upon said cup, a lipstick mass within the cup, a movable cap for the open top of the housing, a sliding flexible strip connecting the movable cap to the

movable cup for moving the latter upwardly in the housing to project the lipstick mass above the open top of the housing for use, said flexible strip and resilient means coacting to snap the cap shut when the cap is in a predetermined position at the open upper end of the housing, said housing being provided with longitudinal guide means for the flexible strip and for the movable cap, said open top of the housing having a seat substantially at right angles to the guide means, the lower portion of one end of the cap being pivotally connected to one end of the flexible strip, said connection being substantially in line with the guide means when the cap is in a closed position on said seat, said resilient means causing the cup to rebound when the cup is moved to its lowered position within the housing.
